UNITED STATES PATENT OFFICE.

THEODORE W. FOSTER, OF PROVIDENCE, RHODE ISLAND.

DESIGN FOR A METAL MIRROR-BACK, &c.

SPECIFICATION forming part of Design No. 26,275, dated November 17, 1896.

Application filed October 9, 1896. Serial No. 608,415. Term of patent 31 years.

To all whom it may concern:

Be it known that I, THEODORE W. FOSTER, a citizen of the United States, residing at Providence, in the county of Providence and State of Rhode Island, have invented and produced a new and original Design for Metallic Covers for the Backs of Mirrors and Similar Articles, of which the following is a specification, reference being had to the accompanying drawings, forming part thereof.

Figure 1 is a plan view of a metallic cover for the back of a mirror, showing my design. Fig. 2 is a transverse section of the same.

The leading feature of my design consists in the heart-shaped outline ornamented along its edges by a raised border formed of curved leaves interspersed with graduated ornaments.

In the drawings, Fig. 1, the foliated scroll 3, with the curved row of beads 4 and the upward-projecting pyramid of graduated beads, is placed at the lower point of the heart. On each side the leaves 6 6 curve inward from the border-line toward the central panel, and the graduated beads 7 7 also curve inward between the leaves 6 6. On each side the

foliated scrolls 8 8, with two lines of graduated beads, continue the border and join the upper ornamentation, consisting of the two foliated scrolls 9 9, having a curved line of beads, and these scrolls, abutting in the depressed point at the upper center of the heart, terminate in the pyramidal graduated beads. The curved leaves 12 and the graduated beads 13 fill up the space between the foliated scrolls 9 9 and 8 8, the whole forming an ornamental border of foliage, the lines of which curve from the edge inward to the central panel.

Having thus described my design, I claim as new and desire to secure by Letters Patent—

The design for a metal back for mirrors and similar articles herein shown and described.

In witness whereof I have hereunto set my hand.

THEODORE W. FOSTER.
